UNITED STATES PATENT OFFICE

NORMAN V. CHRISTENSEN AND FREDERICK F. ZEIER, OF CHICAGO, ILLINOIS, AS
SIGNORS TO UNION SPECIAL MACHINE COMPANY, OF CHICAGO, ILLINOIS, A COR-
PORATION OF ILLINOIS

SEWING MACHINE

Continuation of application Serial No. 270,446, filed April 16, 1928. This application filed March 25, 1929. Serial No. 349,795.

The invention relates to new and useful improvements in sewing machines for stitching at the edge of a fabric. The present application is a continuation of our prior application, Serial Number 270,446, filed April 16, 1928.

An object of the invention is to provide a machine of the above type of comparatively few parts which are positively connected to an actuating shaft whereby said parts may be driven at a relatively high speed without producing excessive vibrations in the machine.

A further object of the invention is to provide a machine of the above type having a four motion feeding mechanism, a needle, and complementary stitch forming devices wherein all of the parts are actuated from a shaft located above the work support and by positive connections therewith.

20 A further object of the invention is to provide a machine of the above type with a supporting standard for the actuating shaft, which standard is located at one side of the line of feed and substantially in rear of the stitching point so as to provide clearance space for the free passage of the material being stitched.

25 A further object of the invention is to provide a machine of the above type wherein the actuating shaft is disposed so as to extend in the general direction of the feed and located substantially in rear of the stitching point in order that the operated parts beneath the work support may be actuated by direct connections.

30 A further object of the invention is to provide a machine of the above type wherein the needle bar is inclined rearwardly from the stitching point and the actuating shaft is disposed not only so as to extend in the general direction of the feed and in rear of the stitching point but also in a direction at right angles to the inclined needle bar.

35 A further object of the invention is to provide a machine of the above type wherein the actuating shaft is mounted in journaled bearings adjacent the ends thereof, which journaled bearings are carried by spaced arms formed integral with the standard located in a vertical plane at one side of the line of feed

and extending in the same general direction as the feed.

These and other objects will in part be obvious and will in part be hereinafter more fully disclosed.

In the drawings, Fig. 1 is a view partly in side elevation and partly in section along the line of feed with the cover plates for the upper portion of the machine removed.

Fig. 2 is a view partly in front elevation and partly in section on a line at right angles to the line of feed substantially at the stitching point and with the cover plate for the upper portion of the machine removed.

Fig. 3 is a sectional view on the line 3—3 of Fig. 2.

Fig. 4 is a top plan view of a portion of the machine with the cover plate for the upper portion of the machine removed.

Fig. 5 is a view from the front of the machine of a portion of the bed plate showing the manner of mounting the lower trimming device and strip deflector, and also in section the cloth plate and latch for holding the same in closed position.

Fig. 6 is a vertical sectional view through the upper section of the machine in a plane passing through the actuating shaft.

Fig. 7 is a view from the end of the actuating shaft showing the needle head, the presser bar spring and the presser bar in section, the needle bar and actuating mechanism therefor being omitted.

Fig. 8 is a view partly in top plan of the needle head and partly in section through the link connection to the needle bar.

General structure

The invention relates to an improvement in sewing machines, and more particularly, to an improvement in a sewing machine which is adapted for stitching at the edge of a fabric. The machine includes a work support on which the fabric rests while it is being stitched. The fabric is fed across the work support by a feeding mechanism which is of the four motion type, and includes both a main and an auxiliary feed dog, which preferably have differential feeding movements imparted thereto. The material is held on

the work support by a presser foot carried at the outer end of a lever arm which is spring pressed toward the work support. This presser foot may be raised by suitable treadle connections. Feeding movements are imparted to the feed dogs by a feed rocker. The machine is especially adapted for forming overedge stitches. The present illustrated embodiment of the invention is for this purpose and the stitch forming mechanism includes a needle which reciprocates in a line inclined to the plane of the work support. Cooperating with the needle beneath the work support is a looper preferably of the thread carrying type and cooperating with this lower looper is an overedge looper which is likewise preferably of the thread carrying type. The overedge looper, in turn, cooperates with the needle. The fabric being stitched is trimmed prior to the stitching of the same. This is accomplished by the aid of a stationary trimming blade carried by the work support or bed plate beneath the same, and a movable trimming blade which is carried by an arm located above the work support. The movable blade is carried by a lever arm fulcrumed adjacent the rear side of the work support. The lever arm is connected to the feed bar for raising and lowering the feed dogs. All of the parts referred to are operated by a single actuating shaft which is disposed above the plane of the work support. The shaft is mounted in bearings carried by a standard, which standard is mounted on the bed of the machine and located at one side of the line of feed in rear of the stitching point so that clearance for the material being stitched is afforded. This shaft extends in the general direction of the feed, but lies in a vertical plane which is inclined to the vertical plane containing the line of feed. The shaft also lies in a line which is inclined to the plane of the work support. The shaft is so positioned that it may be directly connected to an arm extending forward from the feed rocker to a point beneath the shaft. The shaft is also directly connected to the lever arm which vibrates the trimming blade and raises and lowers the feed bar and this connection is directly beneath the shaft. The loopers are operated by an oscillating arm, the end of which is directly beneath the actuating shaft and is oscillated by an eccentric strap cooperating with an eccentric member on said shaft. The needle bar is reciprocated by a link which is directly connected to a crank on the end of the shaft. Thus it is that all of the actuated parts are directly connected to the actuating shaft.

vertically to a point adjacent the upper end of the machine. This standard carries a bracket arm 4 at the rear side thereof and a bracket arm 5 at the front side thereof. In these bracket arms 4 and 5 are the journal bearings for the actuating shaft 6 of the machine. The actuating shaft 6 carries a belt wheel 7 by which it is rotated. This constitutes the general frame of the machine on which all the actuated parts are mounted. As clearly shown in the drawings, the standard 3 is disposed at one side of the line of feed and in rear of the stitching point. This positioning of the standard which carries the actuating shaft at one side of the line of feed, gives ample clearance for the material being stitched so that it may be fed continuously through the machine and past the standard.

Feeding mechanism

Frame structure

The machine includes a supporting bed 1 on which is mounted a work support 2. At the right hand side of the bed plate as viewed in Fig. 2 there is a standard 3 which extends

members are sufficiently at one side of the line of feed as not, in any way, to interfere with the free movement of the fabric across the work support. The arm 15 extends in a direction substantially lengthwise of the actuating shaft. The connecting stud 17 between the arm and the eccentric strap is adjustable lengthwise of the arm and, therefore, in a direction so that the shifting of the eccentric strap for adjusting the length of feed is accomplished by a movement of the eccentric strap laterally of the plane of rotation of the eccentric. The adjustment of the eccentric strap for varying the length of the feed does not disturb the timing of the feed relative to the movement of the needle. The feed dog 9 will be referred to as the auxiliary feed dog, so as to distinguish it from the main dog 8. This auxiliary feed dog 9 is carried by a lever 20 and is capable of vertical adjustment thereon. This lever 20 is fulcrumed on a member 21 carried by the main feed bar 10. The feed bar lever 20 carrying the auxiliary feed dog is provided with a projecting rod 22 which slides freely in a sleeve 23. This sleeve 23 is pivotally mounted on an arm 24 which, in turn, is adjustably fixed to a lug 25 carried by the bed of the machine and the arm may be adjusted and held set in adjusted position by lock nuts 26.

Both feed bars are raised and lowered simultaneously by means of a link 27. This link 27 engages the outer end of the pin member 21. When the link is raised and lowered through an actuating means therefor which will be described later, the feed bars are raised and lowered. When the feed bars move back and forth the rod 22 will slide in the sleeve 23 and change the angular position of the feed bar lever arm carrying the auxiliary feed dog, and this will cause the auxiliary feed dog to be lowered from engagement with the material at an earlier period in the cycle of travel than the main feed dog. Thus it is that the main feed dog has a slightly longer fabric feeding stroke and will gather in the material sufficiently to overcome any stretching thereof. The differential feeding mechanism operates in the usual manner on the fabric. The specific feeding mechanism shown and described forms no part per se of the present invention but is shown and described in an application filed on the 26th day of June, 1928, Serial Number 288,419.

Stitch forming mechanism

The material is fed across the work support to be stitched by a stitching mechanism which forms overseaming stitches. This stitch forming mechanism includes a needle 28 carried by a needle bar 29. The needle bar 29 is mounted for reciprocation in a sleeve bushing 30. The sleeve bushing 30 is rigidly fixed to a projecting lug 31 carried by the needle head 32 and the needle head 32 is formed integral with the bracket 5. The bushing is secured in the needle head by means of a set screw 33. At the upper end of the needle bar there is a collar 34 which carries a projecting pin 35 and a link 36 engages said pin. This pin 35 projects beyond the link 36 and is slotted so as to form parallel faces as indicated at 37 in Fig. 7. This projecting portion of the pin 35 slides freely up and down in a guiding recess 38. The guiding recess is formed by a projecting ledge 39 integral with the needle head and a plate 40 which is secured to the needle head. The so plate and ledge are spaced so as to form the recess 38. This construction affords a means for guiding the upper end of the needle bar and also preventing the needle bar from rotation and in this way takes much of the strain from the operating link 36. It is noted that there is no bearing at the upper end of the needle bar and the needle bar is supported solely by the sleeve bushing referred to above.

The link 36 at its other end is connected to a crank 41 carried by a disc 42 formed as a part of the actuating shaft 6. As the actuating shaft rotates, the needle bar will be reciprocated in its supporting bushing.

Cooperating with the needle beneath the work support is a thread carrying looper 43. Said thread carrying looper 43 is mounted on a looper carrier 44. This looper carrier 44 is mounted on a shaft 45, and the shaft 45 is mounted in suitable lugs carried by the bed of the machine.

Cooperating with the looper 43 beneath the work support and needle above the work support is an overedge thread carrying looper 46. This looper is mounted on a looper carrier 47 which is clamped to a shaft 48. The shaft is journaled in the lugs 49, 49 (see Fig. 1). The looper carrier 47 is provided with a projecting arm 50 and a link 51 is pivotally connected to this arm at its outer end and also pivotally connected to the looper carrier 44. This connection between the looper carriers causes one carrier to operate the other. The shaft 48 is oscillated and will impart oscillations to the looper carrier 47, and this, in turn, will impart oscillations to the looper carrier 44. These parts are so timed that the needle will pass through the material and throw out its needle thread loop so that the underthread looper 40 will enter the same.

The overedge looper, passes alongside of this underthread looper 40 and enters the loop of thread formed thereby. The overedge looper moves over the work support to a position so that the needle on its next descent will enter the loop of thread formed by said overedge looper. The needle bar reciprocates in a line inclined to the plane of the work support, both of the loopers oscillating in planes per-

pendicular to the work support and at right angles to the line of feed. The looper beneath the work support moves in rear of the path of the needle and this is the proper movement of the looper to enter the needle thread loop. The overedge looper moves in front of the needle path above the work support, and this is the proper position of the overedge looper to enable the needle on its descent to enter into the loop of thread formed thereby.

On the end of the shaft 48 there is an arm 52 which is rigidly attached to the shaft. A link 53 is connected to this arm, and at its other end is connected to a lever 54 fulcrumed at 55 on the bed of the machine. Said lever 54 carries a ball stud 56 intermediate its ends. An eccentric strap 57 engages said ball stud and this eccentric strap cooperates with an eccentric 58 on the main shaft 6. It will be noted that the ball stud 56 lies in a plane directly beneath the center of the shaft 6 as indicated in Fig. 3 of the drawings, and thus it is that said lever which imparts oscillations to both of the loopers is operated by a direct connection with an eccentric on the main shaft.

Trimming mechanism

The fabric is trimmed prior to the overedging of the same, and this is accomplished by a trimming mechanism which includes a stationary trimming blade 59 and a movable trimming blade 60. The stationary trimming blade is fixed to a supporting member 61 which is mounted in a bracket 62 carried by the bed of the machine. This member 61 is capable of endwise adjustment in its supporting bracket and is adjusted by means of a screw 63. Said member is clamped in its adjusted positions by a set screw 64. The movable blade 60 is carried by a lever arm 65 which is fulcrumed on a supporting member 66 rigidly connected to the bracket 14. Said lever arm 65 has a relatively long hub member which engages the support and this causes the lever arm to swing in a vertical plane. The movable trimming blade is carried by a head 67 which is mounted on a rod 68. The rod 68 is free to reciprocate in the yoke head 69 at the outer end of the lever arm 65. A spring 70 is coiled about this rod and bears at its outer end against one member of the yoke head. This spring at its other end bears against the collar 71 fixed to the rod 68. The spring normally presses the movable trimming blade laterally against the stationary trimming blade and thus holds the blades in shearing contact with each other. Suitable means is provided, of course, for preventing the member 68 from turning in the yoke head so that the movable blade will be held in proper position to cooperate with the stationary blade.

The lever arm 65 is oscillated by means of

an eccentric strap 72 which cooperates with an eccentric 73 on the actuating shaft 6. This eccentric strap is connected to a ball stud 74 attached to the lever arm 65 by suitable lock nuts 75. This stud projects beyond the ball head thereon with which the eccentric strap cooperates and the link 27 is connected thereto. Thus, it is that the eccentric strap 72 not only oscillates the lever arm supporting the movable trimming blade, but it also moves the link 27 endwise and raises and lowers the feed dogs. It will be noted that the link 27 is in a measure an extension of the eccentric strap 72, that is, they are substantially in alignment. It will also be noted that the connection to the arm supporting the trimming blade is at a point directly beneath the actuating shaft, and these parts are directly connected to said actuating shaft. A downward movement of the eccentric strap 72 will impart a downward movement to the lever arm carrying the trimming blade, and this will cause a severing of the fabric. This downward movement of the eccentric strap imparts an idle movement to the feed dogs, as it lowers the feed dogs from engagement with the material. An upward movement of the eccentric strap will raise the feed dogs and as the feed dogs work against a presser foot which is spring pressed downward, the strain incident to the operation of the feed dogs comes on the eccentric during this upward movement of the eccentric strap. At this time, the trimming blade is on its idle movement. Thus, it is that the eccentric cooperating with the eccentric strap 72 will perform its work at substantially diametrically opposite points. This not only distributes the work on the shaft, but also aids in the counterbalancing of the lateral strains on the shaft.

The trimmed off strip is caused to engage a deflecting cover plate 76 which protects the operating parts beneath the work support and the strip is deflected forwardly toward the front of the machine.

Presser foot mechanism

The material is held on the work support by a presser foot 77. This presser foot is carried by an arm 78 which is mounted on a shaft 79. The shaft 79 is, in turn, journaled in the standard 3, and extends outside of the standard. The portion of the shaft outside of the standard is provided with an arm 80 which is rigidly connected thereto. Also mounted on the outer face of the standard 3 is a lift lever 81. Said lever is fulcrumed at 82, and is provided with a projecting end 83 which lies underneath the arm 80. This lift lever is connected through suitable means with a treadle or knee shift. A spring 84 coiled about the pivotal support for the lift lever is engaged with said lever at one end and a pin or abutment 85 at its other end,

The spring normally turns the lever in a clockwise direction as viewed in Fig. 1. When the outer end of the lift lever is depressed it will engage the arm carrying the 5 presser bar and raise the same.

A coil spring 86 is located in a suitable recess in the needle head and bears against the upper face of the arm 78. The upper end of the coil spring 86 engages a threaded sleeve 10 87 and by adjusting this sleeve in the needle head the tension on the spring may be varied.

The operation of the machine is thought to be obvious from the above description. The fabric is placed on the work support underneath the presser foot and will be fed in 15 a direction at an angle slightly acute to a vertical plane containing the axis of the actuating shaft. As shown in Fig. 3 the direction of feed is longitudinally of the feed dogs 20 shown in this figure, and also longitudinally of the feed bars shown in this figure. The trimming mechanism will trim the material before it reaches the stitching mechanism, and the trimmed-off strip will be deflected to-

ward the front of the machine. The stitching mechanism as shown will form a three thread covering stitch. It will be obvious, of course, that other forms of stitching mechanisms may be used for covering the edge of 30 the fabric. The essential feature consists in the arrangement of the stitching elements so that they are actuated by devices directly connected with the actuating shaft above the work support. Suitable cover plates are pro-

35 vided for attachment to the frame parts of the machine so that the actuating parts are all completely housed. The actuated parts for moving the feed dog back and forth include the bracket arm carried by the feed 40 rocker and the end of this arm is directly beneath the actuating shaft. The actuated parts for raising and lowering the feed bars include a ball stud on the lever arm carrying the trimmer and this is directly beneath the 45 actuating shaft. The actuated parts for the loopers include the rock shaft carrying a ball stud which is likewise directly beneath the actuating shaft. Thus, it is that devices cooperating with the eccentric members on

50 the actuating shaft will impart a downward vertical thrust to these respective actuated trains of mechanisms. The three eccentric members which accomplish the actuation of these parts are mounted on the shaft between 55 the bracket arms in which the shaft is journaled. The needle bar is also actuated by a direct thrust from an eccentric member on the end of the shaft. Thus, it is that the power effort of the actuating shaft is distributed 60 along the shaft and so balanced that the shaft will run very smoothly and freely even at high speed and with little or no vibration incident to the actuation of the parts of the machine.

65 The cover plate for the needle mechanism

is indicated in broken lines in Figs. 1 and 6. There is a cover plate attached by suitable screws threaded into the openings 88 and this cover plate will cover the shaft and the actuated parts directly beneath the same. The 70 work support is mounted to swing about a vertical pivot 89 located at the rear of the machine and said work support is held in closed position by means of a yielding latch 90 which cooperates with a projection 91 on the bracket 62. Suitable tension devices 92 and 93 are provided for the looper threads and the looper threads pass through suitable guides and the oscillating devices 94 and 95 respectively to the loopers. The needle 75 thread passes through a tension 96 and through suitable guides and controlling devices therefor. The thread handling devices associated with the needle and loopers form no part of the present invention and will not be further described. While we have shown eccentrics and cooperating eccentric straps for actuating the feeding mechanism, trimming mechanism and complementary stitch forming devices, and have shown a crank for 80 operating the needle bar, it will be understood that other forms of actuating members may be substituted for these specific forms so long as said actuating members are of a character which will transform the rotary motion 85 of the actuating shaft into the desired back and forth motion necessary to operate the mechanisms described; the term "eccentric members" where used throughout our description and claims defines such actuating 90 members. While we have shown and described in detail an overedge stitch forming mechanism, and the present invention is particularly adapted for operating such mechanisms as is necessary to feed the fabric and 95 form the overedge stitch, it will be understood that from certain aspects of the invention, other types of stitch forming mechanism may be used, and other types of feeding mechanism may be used without departing from the 100 spirit of the invention as set forth in the appended claims. It will be obvious that the arrangement of the shaft above the work support and in rear of the stitching point and extending in the general direction of the line 105 of feed, lends itself particularly to the direct operation of the feeding mechanism and the parts of the stitching mechanism which are beneath the work support by direct connections therewith from the actuating shaft, 110 as well as the direct operation of the needle bar which is above the work support. By placing the standard at one side of the line of feed and inclining the shaft in the manner described, the actuating parts transmitting 115 motion from the actuating shaft to the parts beneath the work support, may also be placed at one side of the line of feed, and thus give ample clearance for the fabric being stitched 120 to pass continuously through the machine. 125

When the stitching is confined to the edge of the fabric, only a small clearance space is necessary, and therefore, the standard and actuated parts may be placed comparatively close to the line of feed and a very effective arrangement obtained for driving the parts beneath the work support.

It is obvious that minor changes in the details of construction and arrangement of the parts may be made without departing from the spirit of the invention as set forth in the appended claims.

Having fully described our invention, what we claim as new and desire to secure by Letters Patent, is:—

1. The combination of a work support, a stitch forming mechanism, a feeding mechanism, an actuating shaft arranged above the plane of the work support and disposed so as to extend in the general direction of the feed and located substantially in rear of the stitching point, actuating members carried by said shaft and devices operated thereby for operating, respectively, the feeding mechanism and the stitching mechanism, and a supporting standard for the actuating shaft arranged to one side of the line of feed whereby clearance for the material being stitched is afforded.
2. The combination of a work support, a stitch forming mechanism, a feeding mechanism, an actuating shaft arranged above the plane of the work support and disposed so as to extend in the general direction of the feed and located substantially in rear of the stitching point, actuating members carried by said shaft and devices operated thereby for actuating the parts of the feeding mechanism and stitching mechanism beneath the work support, and a supporting standard for the actuating shaft, said standard and said devices being arranged to one side of the line of feed whereby clearance for the material being stitched is afforded.
3. The combination of a work support, a stitch forming mechanism, a feeding mechanism, an actuating shaft arranged above the plane of the work support and extending in the general direction of the feed, said shaft being located substantially in rear of the stitching point and disposed in a vertical plane cutting the line of feed at an acute angle at the stitching point, actuating members carried by said shaft, devices operated thereby for operating, respectively, the feeding mechanism and stitching mechanism, and a supporting standard for the actuating shaft arranged to one side of the line of feed whereby clearance for the material being stitched is afforded.

4. The combination of a work support, a stitch forming mechanism including a needle bar and a needle carried thereby, a complementary stitch forming mechanism mounted beneath the work support, a feeding mecha-

nism mounted beneath the work support, an actuating shaft arranged above the plane of the work support and disposed so as to extend in the general direction of the feed and located substantially in rear of the stitching point, actuating members carried by said shafts, and devices operated thereby for operating the complementary stitching mechanism and the feeding mechanism, an actuating device carried by the shaft for operating the needle bar, and a standard for supporting the actuating shaft, said standard and devices for operating the parts beneath the work support being disposed at one side of the line of feed whereby clearance for the material being stitched is afforded.

5. The combination of a work support, an overedge stitch forming mechanism, a feeding mechanism, an actuating shaft arranged in rear of the stitching point and in a vertical plane at an acute angle to the line of feed and carrying actuating members, and devices directly connected to the actuated parts of the stitch forming mechanism and feeding mechanism and cooperating with said actuating members.

6. The combination of a work support, an overedge stitch forming mechanism, a feeding mechanism, a trimming mechanism, an actuating shaft arranged in rear of the stitching point and in a vertical plane at an acute angle to the line of feed and carrying actuating members, and devices directly connected to the actuated parts of the stitch forming mechanism, feeding mechanism, and trimming mechanism and cooperating with said actuating members.

7. The combination of a work support, an overedge stitch forming mechanism, a feeding mechanism, an actuating shaft arranged in rear of the stitching point and in a vertical plane at an acute angle to the line of feed and carrying actuating members, and devices directly connected to the actuated parts of the stitch forming mechanism and feeding mechanism and cooperating with said actuating members, said devices being disposed substantially in a vertical plane and operating the actuated parts by a direct thrust thereon.

8. The combination of a work support, an overedge stitch forming mechanism, a feeding mechanism, a trimming mechanism, an actuating shaft arranged in rear of the stitching point and in a vertical plane at an acute angle to the line of feed and carrying eccentric members, and devices directly connected to the actuated parts of the stitch forming mechanism, feeding mechanism, and trimming mechanism and cooperating with said eccentric members, said devices being disposed substantially in a vertical plane and operating said actuated parts by a direct thrust thereon.

9. The combination of a bed plate, a work

support carried thereby, an overedge stitch forming mechanism, a feeding mechanism, a standard carried by the bed plate and having spaced laterally projecting bracket arms, an actuating shaft journaled in said bracket arms and arranged in a vertical plane at an acute angle to the line of feed, said shaft having eccentric members thereon between said bracket arms and an eccentric member on the end of the shaft, devices directly connected to the actuated parts of the stitch forming mechanism and feeding mechanism and cooperating with said eccentric members.

10. The combination of bed plate, a work support carried thereby, an overedge stitch forming mechanism, a feeding mechanism, a trimming mechanism, said bed plate having a standard lying in a plane parallel with the line of feed and having laterally projecting bracket arms, an actuating shaft journaled in said bracket arms and disposed in a vertical plane at an acute angle to the line of feed, eccentric members on said shaft between said bracket arms, an eccentric member on the end of the shaft, and devices directly connected to the actuated parts of the stitch forming mechanism and feeding mechanism and cooperating with said eccentric members.

30 11. The combination of a bed plate, a work support carried thereby, an overedge stitch forming mechanism, a feeding mechanism, a trimming mechanism, a standard carried by said bed and having spaced laterally projecting bracket arms, an actuating shaft journaled in said bracket arms and arranged in a vertical plane at an acute angle to the line of feed, eccentric members carried by said shaft between said bracket arms, an eccentric member on the end of said shaft, and devices directly connected to the actuated parts of the stitch forming mechanism, the feeding mechanism, and trimming mechanism and cooperating with said eccentric members.

45 12. The combination of a bed plate, a work support carried thereby, an overedge stitch forming mechanism, a feeding mechanism, a trimming mechanism, said bed plate having a standard lying in a plane parallel with the line of feed and having laterally projecting bracket arms, an actuating shaft journaled in said bracket arms and disposed in a vertical plane at an acute angle to the line of feed, eccentric members on said shaft between said bracket arms, an eccentric member on the end of the shaft, and devices directly connected to the actuated parts of the stitch forming mechanism and feeding mechanism and cooperating with said eccentric members, said devices being disposed substantially in a vertical plane whereby the actuated parts are operated by a direct vertical thrust from said eccentric members.

55 13. The combination of a bed plate, a work support carried thereby, an overedge stitch

forming mechanism, a feeding mechanism, a trimming mechanism, a standard carried by said bed plate and having spaced laterally projecting bracket arms, an actuating shaft journaled in said bracket arms and arranged in a vertical plane at an acute angle to the line of feed, eccentric members carried by said shaft between said bracket arms, an eccentric member on the end of said shaft, and devices directly connected to the actuated parts of the stitch forming mechanism, the feeding mechanism, and trimming mechanism and cooperating with said eccentric members, said devices being disposed substantially in a vertical plane whereby the actuated parts are operated by a direct vertical thrust from said eccentric members.

14. The combination of a work support, a needle bar and a needle carried thereby, a complemental overedge stitch forming device mounted beneath the work support, a feeding mechanism, a trimming mechanism, an actuating shaft arranged above the work support in rear of the stitching point and in a vertical plane at an acute angle to the line of feed, an eccentric member on the end of the shaft and a link directly connecting said eccentric member to the needle bar, an eccentric member on said shaft intermediate the ends thereof, a device cooperating therewith and directly connected to the actuated parts of the complemental stitch forming mechanism, and a means for operating the feeding mechanism from said shaft.

15. The combination of a work support, a needle bar, a needle carried thereby, a complemental overedge stitch forming mechanism mounted beneath the work support, a four motion feeding mechanism mounted beneath the work support, an actuating shaft arranged above the work support in rear of the stitching point and in a vertical plane at an acute angle to the line of feed, an eccentric member at the end of the shaft, a link connecting said eccentric member to the needle bar, eccentric members carried by the shaft intermediate the ends thereof and devices operated thereby for operating the actuated parts of the complemental stitch forming mechanism and the actuated parts of the four motion feeding mechanism.

16. The combination of a work support, a needle bar, a needle carried thereby, a complemental overedge stitch forming mechanism, a four motion feeding mechanism, a trimming mechanism including a movable trimming blade, an actuating shaft arranged above the work support and in a vertical plane at an acute angle to the line of feed, an eccentric member on the end of the shaft, a link connecting the same to the needle bar, a second eccentric member on the shaft, a device connecting said second eccentric member directly to the actuated parts of the complemental stitch forming mechanism, a third

eccentric member on said shaft, devices for connecting said third eccentric member directly to the actuated parts of the feeding mechanism for imparting feed movements thereto, a fourth eccentric member on said shaft and devices for connecting said fourth eccentric member directly to the actuated parts operating the movable trimming blade and the actuated parts for raising and lowering the feed dogs.

17. The combination of a work support, an overedge stitch forming mechanism, a feeding mechanism including a main feed bar, a feed rocker, an arm carried by said rocker and projecting therefrom, an actuating shaft arranged in rear of the stitching point and in a vertical plane at an acute angle to the line of feed, the end of said arm lying substantially in said plane, an eccentric member on the shaft, a device operated by said eccentric member and directly connected to said arm for oscillating the rock shaft, means actuated by said shaft for raising and lowering the feed bar, and means actuated by said shaft for operating the overedge stitch forming mechanism.

18. The combination of a work support, an overedge stitch forming mechanism, a feeding mechanism including a main feed bar, a feed rocker, an arm carried by said rocker and projecting therefrom, an actuating shaft arranged in rear of the stitching point and in a vertical plane at an acute angle to the line of feed, the end of said arm lying substantially in said plane, an eccentric member on the shaft, a device operated by said eccentric member and directly connected to said arm for oscillating the rock shaft, means actuated by said shaft for raising and lowering the feed bar, means actuated by said shaft for operating the overedge stitch forming mechanism, a trimming mechanism for trimming the fabric in advance of the stitching of the same, and a means for actuating said trimming mechanism from said shaft.

19. The combination of a work support, a needle bar, a needle carried thereby, a complementary overedge stitch forming mechanism, actuated parts therefor, including a lever having a ball stud, an actuating shaft located above the work support in rear of the stitching point and in a vertical plane at an acute angle to the line of feed, said ball stud being disposed in said vertical plane, an eccentric member on said shaft, a device actuated thereby and connected to said ball stud, means for operating the needle from said shaft and means for operating the feed from said shaft.

20. The combination of a work support, an overedge stitch forming mechanism, a feeding mechanism including a feed bar, a trimming mechanism including a movable trimming blade, a lever arm carrying said movable blade, a ball stud mounted on said

lever arm, means for raising and lowering said feed bar from said ball stud, an actuating shaft arranged above the work support and in a vertical plane at an acute angle to the line of feed, said ball stud being disposed substantially in said vertical plane, an eccentric member on said shaft, a device cooperating therewith and connected to said ball stud, means operated by said actuating shaft for moving the feed dog back and forth, and means actuated by said shaft for operating the overedge stitch forming mechanism.

21. The combination of a bed plate, a work support carried thereby, a standard carried by said bed and having spaced laterally projecting bracket arms, an actuating shaft journaled in said bracket arms and disposed in a vertical plane at an acute angle to the line of feed, a feeding mechanism, a needle bar, a needle carried thereby, a complementary overedge stitch forming mechanism, a sleeve bushing carried by one of said bracket arms in which said needle bar reciprocates, a collar on the upper end of said arm and an eccentric member on the end of the shaft, a link connecting said eccentric member to said collar, means actuated by the shaft for operating the feeding mechanism, and means actuated by said shaft for operating the complementary overedge stitch forming mechanism.

22. The combination of a bed plate, a work support carried thereby, a standard carried by said bed and having spaced laterally projecting bracket arms, an actuating shaft journaled in said bracket arms and disposed in a vertical plane at an acute angle to the line of feed, a feeding mechanism, a needle bar, a needle carried thereby, a complementary overedge stitch forming mechanism, a sleeve bushing carried by one of said bracket arms in which said needle bar reciprocates, a collar on the upper end of said arm and an eccentric member on the end of the shaft, a link connecting said eccentric member to said collar, means actuated by the shaft for operating the feeding mechanism, and means actuated by said shaft for operating the complementary overedge stitch forming mechanism, said collar on the needle bar having a projecting member and said bracket arm carrying the bushing having a guiding recess for said member which prevents the needle bar from oscillating in its reciprocations.

23. The combination of a work support, an overedge stitch forming mechanism, a feeding mechanism including a feed bar, a feed dog carried thereby, a trimming mechanism including a movable trimming blade, an actuating shaft arranged in a vertical plane at an acute angle to the line of feed, an eccentric member carried by said shaft, a device cooperating with said eccentric member and connected to said movable trimming blade and to said feed bar for raising the feed dog

on the upward movement of said device, and for actuating the trimming blade to sever the fabric on the downward movement of the trimming device, means operated by said shaft for moving said feed bar back and forth, and means operated by said shaft for actuating the overedge stitch forming mechanism.

24. The combination of a work support, an overedge stitch forming mechanism, a differential feeding mechanism, a trimming mechanism, an actuating shaft arranged in a vertical plane at an acute angle to the line of feed and carrying eccentric members, devices directly connected to the actuated parts of the stitch forming mechanism, the differential feeding mechanism and the trimming mechanism and cooperating with said eccentric members.

25. The combination of a supporting bracket, spaced bracket arms projecting laterally therefrom, an actuating shaft journaled in said bracket arms and carrying an actuating belt wheel at one end thereof, a needle bar located in a vertical plane containing the axis of said shaft and at the opposite end from said belt wheel, an eccentric member on said shaft, a link connecting said eccentric member to said needle bar, a work support, a feeding mechanism, said feeding mechanism being disposed so as to feed the material in a line at an acute angle to a vertical plane containing the needle bar and axis of the shaft, a complemental stitch forming mechanism, means operated by the shaft for actuating said feeding mechanism and means operated from the shaft for actuating the complemental stitch forming mechanism.

26. The combination of a work support, a stitch forming mechanism, a feeding mechanism including a feed rocker located beneath the work support, a feed bar connected to the feed rocker, an actuating shaft arranged above the work support in rear of the stitching point and in a vertical plane at an acute angle to the line of feed, means operated by said shaft for actuating the stitch forming mechanism, a device directly connecting said shaft and feed rocker for oscillating the feed rocker, and devices actuated by said shaft and connected to said feed bar for raising and lowering the same, said last-named devices being arranged substantially in a straight line so as to provide a direct lifting thrust for the feed bar.

27. The combination of a work support, a stitch forming mechanism including a needle and a looper cooperating with the needle beneath the work support, a feeding mechanism including a feed rocker, a feed bar connected to the feed rocker, an actuating shaft arranged above the work support in rear of the stitching point and in a vertical plane at an acute angle to the line of feed, an eccentric member on the end of the shaft for actuating

said needle bar and eccentric members intermediate the ends of the shaft for actuating devices for oscillating the feed rocker, lifting the feed bar and imparting oscillations to the looper.

28. The combination of a work support, a stitch forming mechanism including a needle and a looper cooperating with the needle beneath the work support, a feeding mechanism including a feed rocker, a feed bar connected to the feed rocker, an actuating shaft arranged above the work support in rear of the stitching point and in a vertical plane at an acute angle to the line of feed, an eccentric member on the end of the shaft for actuating said needle bar, and eccentric members intermediate the ends of the shaft for actuating devices for oscillating the feed rocker, lifting the feed bar and imparting oscillations to the looper, all of said devices actuated by said eccentrics being disposed substantially in a vertical plane containing the axis of the shaft.

29. The combination of a work support, a feeding mechanism, an overedge stitching mechanism including a needle bar and a needle carried thereby, said needle bar being disposed in a line inclined rearwardly from the stitching point, and complemental stitch forming mechanisms mounted beneath the work support and cooperating with said needle, an actuating shaft arranged above the plane of the work support and disposed so as to extend in the general direction of the feed and located in rear of the needle bar and in a line at right angles to the line of reciprocation of the needle bar, means for reciprocating said needle bar from said shaft, actuating members carried by said shaft, and devices operated thereby for operating the feeding mechanism and the complemental stitch forming mechanism beneath the work support, said devices being disposed at one side of the line of feed whereby clearance for the material being stitched is afforded.

30. The combination of a work support, a feeding mechanism, an overedge stitching mechanism including a needle bar and a needle carried thereby, said needle bar being disposed in a line inclined rearwardly from the stitching point, and complemental stitch forming mechanism mounted beneath the work support and cooperating with said needle, an actuating shaft arranged above the plane of the work support and disposed so as to extend in the general direction of the feed and located in rear of the needle bar and in a line at right angles to the line of reciprocation of the needle bar, means for reciprocating said needle bar from said shaft, actuating members carried by said shaft, and devices operated thereby for operating the feeding mechanism and the complemental stitch forming mechanism beneath the work support, and a standard for supporting said

actuating shaft, said standard and said devices being disposed at one side of the line of feed whereby clearance for the material being stitched is afforded.

5 31. The combination of a work support, a needle, a looper cooperating with the needle beneath the work support, a looper cooperating with the first-named looper and with the needle above the work support to form overedge stitches, a feeding mechanism including a main feed dog and an auxiliary feed dog having a differential feeding movement, an actuating shaft arranged above the plane of the work support and disposed so as to extend in the general direction of the feed and located substantially in rear of the stitching point, actuating members carried by said shaft, and devices operated thereby for operating, respectively, the needle, loopers and 20 the feed dogs, and a supporting standard for the actuating shaft arranged to one side of the line of feed whereby clearance for the material being stitched is afforded.

32. The combination of a work support, a needle, a looper cooperating with the needle beneath the work support, a looper cooperating with the first-named looper and with the needle above the work support to form overedge stitches, a feeding mechanism including a main feed dog and an auxiliary feed dog having a differential feeding movement, an actuating shaft arranged above the plane of the work support and disposed so as to extend in the general direction of the feed and located substantially in rear of the stitching point, actuating members carried by said shaft, and devices operated thereby for operating, respectively, the needle, loopers and the feed dogs, and a supporting standard 35 for the actuating shaft, said standard and said devices operated by said actuating member and imparting movements to the parts beneath the work support being arranged to one side of the line of feed whereby clearance 40 for the material being stitched is afforded.

33. The combination of a work support, a stitch forming mechanism, a feeding mechanism including a feed rocker located beneath the work support, a feed bar connected to the feed rocker and carrying a feed dog, an actuating shaft arranged above the work support and disposed so as to extend in the general direction of feed and located substantially in rear of the stitching point, a supporting standard for the actuating shaft arranged to one side of the line of feed whereby clearance for the material being stitched is afforded, devices operated by said shaft for actuating the stitch forming mechanism, devices actuated by said shaft for raising and lowering the feed dog, an arm carried by the feed rocker, an eccentric on said actuating shaft, an eccentric strap cooperating with said eccentric, means for connecting said eccentric strap to said arm whereby said con-

nexion may be shifted lengthwise of the arm for varying the stroke of the feed dog, said arm extending in a direction substantially lengthwise of the shaft whereby the stroke of the feed dog may be varied without disturbing the timing of the feed dog.

34. The combination of a work support, a stitch forming mechanism, a trimming mechanism including a movable member carrying a trimming blade, a feeding mechanism including a feed bar carrying a feed dog, an actuating shaft arranged above the work support and disposed so as to extend in the general direction of the feed and located substantially in rear of the stitching point, a supporting standard for the actuating shaft arranged to one side of the line of feed whereby clearance for the material being stitched is afforded, devices operated by said shaft for actuating the stitch forming mechanism, devices actuated by said shaft for moving the feed bar back and forth, an eccentric on said shaft, an eccentric strap operated thereby and connected to said member carrying the trimming blade for raising and lowering the trimming blade, and devices connected to said movable member carrying the trimming blade and said feed bar for raising and lowering the feed dog while permitting said feed bar to move back and forth.

In testimony whereof, we affix our signatures.

NORMAN V. CHRISTENSEN.
FREDERICK F. ZEIER.
